UNITED STATES PATENT OFFICE.

HENRY J. GAISMAN, OF NEW YORK, N. Y., ASSIGNOR TO AUTO STROP COMPANY, OF NEW YORK, N. Y., A CORPORATION OF NEW YORK.

SAFETY-RAZOR.

1,158,914.

Specification of Letters Patent.

Patented Nov. 2, 1915.

Application filed June 2, 1909. Serial No. 499,785.

To all whom it may concern:

Be it known that I, HENRY J. GAISMAN, a citizen of the United States, and resident of New York city, borough of Manhattan, in the county of New York and State of New York, have invented certain new and useful Improvements in Safety-Razors, of which the following is a specification.

The object of my invention is to cause the blade in a safety razor to have longitudinal movement or reciprocation in the direction of the blade edge, by and during the movement of the razor along the face.

In carrying out my invention I provide a movable element, which may be the guard adapted to be actuated by contact of the same with the face as the razor is moved along the latter, with means operated by such element for causing reciprocation of the blade whereby to produce a sort of shearing cut.

My invention also comprises the novel details of improvement and combinations of parts that will be more fully hereinafter set forth and then pointed out in the claims.

Reference is to be had to the accompanying drawings forming part hereof, wherein,

Figure 1 is a plan view of a safety razor embodying my invention; Fig. 2 is a cross section substantially on the plane of the line 2, 2, in Fig. 4; Fig. 3 is an inverted plan view, the handle being removed; Fig. 4 is a side view of the razor inverted looking from the left in Fig. 3; Fig. 5 is a cross section substantially on the line 5, 5, in Fig. 3, and Fig. 6 is a detail perspective of the rocking member for reciprocating the blade.

Similar numerals of reference indicate corresponding parts in the several views.

The numeral 1 indicates a suitable frame provided with a handle 2 arranged in any desired manner. At 3 is a rotative element journaled upon frame 1, which element may be the guard to co-act with blade 4, the edge of the blade extending along but out of contact with said element. For this purpose I have shown the element 3 in the nature of a roller provided with any desired number of annular projecting ribs 3^a, the surface of which may be milled or roughened to aid in causing element 3 to rotate when moved in contact with the face, which projecting portions 3^a serve in the nature of guard in connection with the blade edge. In the example illustrated the blade 4 is detachably held

in a reciprocative carriage 5 that is mounted to slide upon frame 1. I have shown said carriage 5 approximately in the nature of a plate upon which blade 4 rests, fingers 5^b projecting from said plate adjacent the corners of the blade upon which the blade rests. Clips 6 at the ends of the blade serve to hold the same in position upon carriage 5, a latch or spring 7 supported by the carriage and bearing against the heel of the blade serving to retain the latter in position between clips 6 and the carriage plate. Carriage 5 is shown provided with means, such as ways, for guiding it upon frame 1, for which purpose I have shown carriage 5 provided with rods 8, 9, that are adapted to be supported by frame 1. I have shown carriage 5 provided with ears or the like 5^a receiving said rods, and frame 1 provided with ears 1^a also receiving said rod, whereby 75 said rods may be secured to the carriage to slide in holes in the ears 1^a, or said rods may be secured to ears 1^a to permit the ears 5^a of the carriage to slide on the rods, although the carriage may be otherwise suitably supported to reciprocate. The arrangement is such that during the reciprocations of the carriage the blade edge may slide in the direction of its length in shaving position with respect to guard 3. The clips 6 are 80 suitably supported in connection with carriage 5, and for this purpose may be attached directly to the carriage or the arms 6 of said clips may be connected by a cross bar 6^b, said arms being swiveled upon rod 9, spring or springs 10 secured to carriage 5 bearing against cross bar 6^b and thus acting to cause clips 6 to bear upon the blade. The latter may be inserted by swinging back 85 the latch or spring 7, sliding the blade forwardly under clips 6 and then raising latch or spring 7 behind the blade.

The means I have shown which reciprocate carriage 5 by and during the rotation of the guard or rotative element 3 are as follows: At 11 is a rocking lever or arm shown pivotally connected with frame 1, as by a pivot or the like 12 passing through a lug 13 on frame 1, and through a hole 11^a in lever or arm 11. Said lever or arm has projections 11^b on opposite sides of pivot 12 which extend in position to be engaged by rotating element 3 that is appropriately arranged to rock the lever or arm 11. For this purpose I have shown element 3 as 110

provided with cranks or eccentric portions 3^b disposed on opposite sides of the axis of said element, and on opposite sides of pivot 12, the cranks or eccentrics 3^b being adapted to engage the corresponding projections 11^b, the element 3 being suitably cut away at 3^c between two adjacent projections 3^a, opposite the cranks or eccentrics, to permit the entrance of projections 11^b. Rock lever 11 or arm 11 is connected with carriage 5, for which purpose I have shown a projection 14 attached to said carriage and having a portion 14^a entering a slot 11^c in lever 11, whereby, as the latter is rocked, carriage 5 will be reciprocated. Any other suitable means may be provided for movably connecting lever or arm 11 with carriage 5 for causing said lever to reciprocate the carriage.

20 In using my improved safety razor, the blade is placed in position so that its cutting edge may be reciprocated along and in shaving position with respect to the rotative guard element 3, and the razor is applied to the face in the customary manner, with the element 3 in contact with the face; then as the razor is drawn along the face said element will be rotated by contact with the face, the cranks or eccentrics 3^b will thereby be revolved and by their contact with projections 11^b of lever or arm 11 the latter will be rocked and thereby the carriage 5 and blade 4 will be reciprocated, so that the blade edge reciprocates in a line substantially transverse to the direction in which the razor is drawn along the face, whereby the usual action of the blade upon the hairs will take place while at the same time the reciprocations of the blade cause 35 substantially the same to act upon the hairs substantially in the nature of a shearing cut, the reciprocations of the blade thus being caused by the rotary action of the element 3.

40 My invention is not limited to the details of construction and arrangements set forth as the same may be varied within the scope of the appended claims, without departing from the spirit of my invention.

Having now described my invention what 45 I claim is:—

50 1. In a safety razor, a frame, means to support a blade, a rotative element in such position to the means for holding the blade as to form a guard for such blade, the said 55 rotative element being operated through engaging the surface being shaved, a lever, means for pivotally mounting the lever at one of its ends near the rotative element, means for swinging the lever in one direction, means for swinging the lever in an opposite direction, and means engaging the lever near its opposite end for communicating the movement of the lever to the blade holder.

65 2. In a safety razor, a frame, a blade

holder thereon, a rotative element adapted to be operated by engaging the surface being shaved and adapted as a guard for the blade, a lever, a pivot near the rotative element on which the lever is mounted, means 70 on the guard for swinging the lever in one direction, means on the guard for swinging the lever in an opposite direction, and means engaging the lever at the end remote from its pivot for communicating the movement 75 of the lever to the blade holder.

3. In a safety razor, a frame, means for supporting a blade, a rotative element adapted as a guard for the blade held by the blade holder, rotatable by engagement 80 with the surface being shaved, a lever, lateral extensions on the lever, means on the guard for engaging one of the lateral extensions, means on the guard for engaging the other lateral extension whereby the 85 lever is oscillated, and means for communicating the movement of the lever to the blade carrier.

4. In a safety razor, a frame, means for supporting a blade, a rotative element 90 adapted as a guard for the blade held by the blade holder rotatable by engagement with the surface being shaved, a lever, lateral extensions on the lever, oppositely disposed means on the guard for engaging the 95 lateral extensions of the lever whereby the rotation of the guard oscillates the lever, and means for communicating the movement of the lever to the blade holder.

5. In a safety razor, a frame, means for 100 supporting a blade, a rotative element adapted as a guard for the blade held by the blade holder rotatable by engagement with the surface being shaved, a lever, lateral extensions on the lever, oppositely disposed cams on the guard for engaging the lateral extensions of the lever whereby the rotation of the guard oscillates the lever, and means for communicating the movement of the lever to the blade holder. 110

6. A safety razor comprising a frame, a blade mounted thereon to reciprocate, a rotary element adapted to engage the face and provided with an eccentric, a lever pivotally carried by the frame and connected 115 with said blade, and means to cause said eccentric to operate said lever.

7. A safety razor comprising a frame, a reciprocative blade-holding carriage mounted thereon, a rotative element carried by the frame in shaving relation to the blade edge, said element having a plurality of eccentrics, and a rocking lever carried by the frame and connected with the carriage, said lever having means to be alternately operated by said eccentrics for rocking the lever. 125

8. A safety razor comprising a frame, a reciprocative blade-holding carriage mounted to reciprocate thereon, a rotary element 130

- provided with annular projections serving as a guard and located parallel and adjacent to the blade edge, said rotative element having eccentrics at opposite sides of its axis, a 5 lever mounted to rock upon the frame and provided with projections on opposite sides to co-act with said eccentrics, and means movably connecting said lever with said carriage for reciprocating the latter.
- 10 9. A safety razor comprising a frame, a reciprocative blade-holding carriage mounted thereon, a rotary guard provided with a series of adjacent annular projections adapted to rotate adjacent the blade edge but free therefrom, said guard having eccentrics, and a rocking lever carried by the frame and connected with the carriage and provided with means to engage said eccentrics to rock said lever.
- Signed at New York city, in the county 15 of New York, and State of New York, this 28th day of May A. D. 1909.

HENRY J. GAISMAN.
